UNITED STATES PATENT OFFICE.

MORTIMER M. ROBB, OF DULUTH, MINNESOTA, ASSIGNOR TO UNION MATCH COMPANY, OF DULUTH, MINNESOTA, A CORPORATION OF MINNESOTA.

BOX-FILLING MACHINE.

No. 906,291.

Specification of Letters Patent.

Patented Dec. 8, 1908.

Application filed January 2, 1908. Serial No. 409,000.

To all whom it may concern:

Be it known that I, MORTIMER M. ROBB, residing in Duluth, in the county of St. Louis and State of Minnesota, have invented new and useful Improvements in Box-Filling Machines, of which the following is a description, reference being had to the accompanying drawings, which are a part of this specification.

10 My invention relates to means for assorting and arranging material for, and putting it into, boxes.

15 The mechanism, herewith shown and described, which embodies a form of my invention, is especially adapted for receiving, assorting, arranging, parallelizing and putting matches, as they are discharged from a match making machine, into boxes, of such size and form as are adapted and commonly 20 used for holding matches for shipping, for sale, and for use.

The invention may be embodied in other equivalent forms of mechanism, and may be employed for boxing other things than 25 matches.

The invention consists in the mechanism, its parts, and combinations of parts, as herein described and claimed, or the equivalents thereof.

30 In the drawings, Figure 1 is an elevation of the improved box-filling machine, looking at it from the front in connection with a fragment of a match machine, of a form with which this form of box-filling machine is 35 adapted to be used. Fig. 2 is a top plan of the box filling machine, parts being broken away for convenience of illustration; and with a fragment of the match machine, in section. Fig. 3 is an enlarged view, partly

40 in longitudinal section, of that part of the box filling machine at the left in Fig. 1; a series of boxes in section being also shown to illustrate how they are fed into and filled by the machine. Fig. 4 is an elevation of the 45 end of a match feed-way, and a section of the tray carrier, with related mechanisms. Fig. 5 is a vertical transverse section from front to rear of the tray carrier and the match feed-way, and related mechanisms being those

50 mostly shown in Fig. 4. Fig. 6 is a vertical section longitudinally of a fragment of the tray carrier and its supporting trough-way and related supporting devices. Fig. 7 is a fragment of the box feeding and applying 55 mechanism, the tray carrier being omitted.

Fig. 8 is a view of the inside of the guide for boxes, and of its elastic fingers shown in Fig. 7, at the right. Fig. 9 is a plan of a fragment of the box runway, shown in position at the left in Figs. 1 and 3. Fig. 10 is a transverse section of this box runway, on line 10—10 of Fig. 9. Fig. 11 is a detail showing one of the feed rollers and the related partitions of the match feed-way, which feed-way is shown in position in Figs. 2, 4 and 5. And Fig. 12 is 65 a detail of a tray carrier-supporting and tension device.

This improved box-filling machine is especially adapted for use with a match machine from which the finished matches are ejected 70 from horizontal rows of the match carrier permitting them to fall therefrom in such manner that they may drop into the tray carrier of this box-filling machine. A match machine of this general character is shown and 75 described in the Wyman patent No. 570,529 of November 3, 1896.

In the drawings, A A represent upright members of the frame of the match machine, and B B represent the perforated plates of an 80 endless match carrier of that machine, from which the finished matches are discharged row by row.

For supporting the box-filling machine mechanism conveniently, and preferably by 85 attaching it to the frame of the match machine, brackets 3, 3 are provided, which brackets are in a generally right angled form, the vertical member of which may be secured to the frame of the match machine by bolts 90 4, 4. A flat elongated horizontally disposed bed 5 rests on the brackets 4, 4 and may be secured thereto by bolts 6. The bed is 95 advisedly provided with a marginal, downwardly-projecting, reinforcing flange 7, and the brackets 3, 3 are provided at the rear ends of their upper members, with transverse recesses 8, 8, adapted to receive the flange 7 therein, and permit of the adjustment of the bed toward the front or rear 100 thereon, the bolt apertures in the brackets providing therefor. This bed extends toward the right and left in front of and past the front of the match carrier formed of the plates B B.

105 Mounted on the bed 5, there is an elongated trough-way 9, adapted to support and carry a tray carrier therein, as hereinafter described. This trough-way is readily and conveniently made of two angle irons or 110

plates 10, 10, one flange or member of each angle iron being made to overlap a corresponding member of the other angle iron to together form the bottom of the way, as shown best in Fig. 5. That portion 11 of the outer upright member or wall of the member 10 of this trough-way, that is opposite the match carrier, is advisably raised a little higher than is necessary for the remainder of the walls of this trough-way, to serve as a guard or wall to prevent matches as they come to this trough-way, from going over it. The upright walls 10, 10 of this trough-way are recessed along their entire lengths near the bottom on the inside thereof, to receive therein and retain against buckling up, the tray carrier hereinafter to be described. This trough-way 9 is provided medially with a supporting block 12 (Figs. 1 and 3) secured rigidly thereto, which block rests on the bed 5, and the trough-way is pivoted to the bed by a bolt 13. At its rear end the trough-way is provided with a block 14 secured to the under side of the trough-way, which block rests and is movable laterally with the trough-way on the bed. Near its front end this trough-way is provided with a dove-tailed transverse slide piece 15 bolted to the under side of the trough-way, which slide fits in a correspondingly dove-tailed channel therefor in a block 16, (Figs. 1, 5, 6,) which block is pivoted on the bed 5 by a bolt 17. A pitman 18 connecting at one end on to a stud bolt 19 fixed in the slide 15 fits and rides at the other end on an eccentric 20 on the shaft 21 mounted vertically in suitable bearings therefor on the bed 5, and provided with a pinion 22 that is geared by a cog wheel to the driving shaft 23. By this means the tray carrier 9, and the parts carried thereon, are caused to oscillate, the vibration or oscillation being reversed on that portion of the tray that is at the left (Fig. 1) of the pivot 13 from what it is at the right of that pivot, and the extent or length of the motion being greater in each case as the distance from the pivot 13 increases. The driving shaft 23 is mounted in hangers 24, 24 secured to and depending from the bed 5, and may be driven from any suitable source of power, conveniently by a sprocket chain 25 running from it to a suitable wheel on a shaft in the match machine.

For receiving the matches as they are discharged and fall from the plates B of the carrier of the match machine, temporary partitioned trays are provided, which being suitably connected together form the endless tray carrier 26. This tray carrier is formed of sheet metal, a single piece or sheet, having its opposite marginal longitudinal edges turned up at right angles to the intermediate portion, which intermediate portion forms the bottom 27 of the tray, the upturned margins forming the side walls 28, 28 thereof, the

side walls 28 being extended longitudinally forming ears 29 at each end of each tray, which ears on one tray overlap those of the abutting tray, and are pivoted thereto by rivets 30 forming the bottoms and side walls 70 of an endless series of trays, or the tray carrier 26. This endless chain of bottoms and side walls, is divided into a continuous and unseparated series of trays and compartments of such size as is desired, by transverse partitions 31, which are conveniently made of a piece of sheet metal provided with a right angled flange 32 at one end to fit on the bottom 27 of a tray, and with other side flanges or wings 33 made to fit against the 75 side walls 28 of the trays, and the partitions are secured to the trays by rivets through these side wings and the side walls of the trays. The partitions 31 project outwardly from the trays a distance substantially equal to the depth of the trays. The upper line of this endless tray carrier 26 fits into and runs along in the trough-way 9, the side walls 28 of the carrier fitting into the recesses in the side walls of the trough-way 9, whereby the 80 carrier is retained in position, against accidental displacement, while traveling in and along the trough-way. This endless tray carrier at its rear end is carried on polygonal wheels 34 which are fixed on the driven shaft 95 35, the shaft being mounted rotatively in brackets 36 which are secured, one at each side, to the bed 5, conveniently by bolts 37 through ears on the brackets. The shaft 35 is rotated intermittently by means of a ratchet wheel 38 tight on the shaft, which is engaged releasably by a click pawl 39 pivoted on a sector arm 40 revolvably loose on shaft 35, the pawl being held to releasable engagement with the wheel by a spring 41. The 100 sector arm 40 is oscillated by a pitman 42 pivoted thereto, and riding at its other end by a strap connection on the eccentric 43 fixed on a shaft 44, which shaft is mounted in hangers 45 secured to and depending from the bed 5. This shaft 44 is provided with a friction disk 46, which is contacted by a friction wheel 47 splined and shiftable on driving shaft 23. The friction wheel 47 is provided with a hub 48 having an annular 105 groove therein in which groove pins ride that are fixed in the furcate fingers of a shifting lever 49. By this arrangement of driving mechanism for the tray carrier, its motion can be timed to adapt it to so pass the match 110 carrier that it will receive the desired number of matches to be put in the boxes when they are transferred from this tray carrier to the boxes. At its other or initial end of its run, the tray carrier 26 is carried on other idle 115 polygonal wheels 50 on axle 51 mounted in radial arms 52 (Figs. 1, 2, 4, 12,) which arms are adjustable endwise and radially on bolts 53 and in channels therefor in crown ratchet toothed disks 54 loose on the bolts 53. The 120 125 130

arms 52 are provided with elongated slots through which the bolt 53 passes, to permit of the endwise adjustment of the arms 52 thereon. Complementary crown ratchet 5 toothed disks 55 are fixed on the respective sides of the trough-way 9, and the disks 54 engage these fixed disks 55 adjustably. The disks 54 are clamped to disks 55 by nuts on bolts 53. By the construction just de- 10 scribed, the arms 52 can be adjusted up or down to suitably regulate the position of the wheels 50 to properly carry the tray carrier on to the trough-way 9, and also the arms 52 can be swung toward the right or left as re- 15 quired to obtain the proper tension in the tray carrier.

For transferring the matches X when discharged from the plates B of the match carrier to the tray carrier 26, a match feed-way, 20 as wide as the entire stream of matches being discharged thereon, is provided, which is adapted to transport the matches in the same endwise position in which they are discharged from the match carrier, by active means of 25 propulsion, and so guiding them that they cannot swing or slue around until they are discharged from this feed-way into the compartments of the tray carrier, which compartments are made so narrow as to prevent 30 the matches from sluing around after they have been deposited in these carrier trays. In this match feed-way a series of rollers 56 are journaled in two frame plates 57, (Figs. 2, 4, 5, 11,) which frame plates rest on and 35 are secured to the bed 5. These rollers are arranged parallel to each other and near together, and so that the plane of their axes is inclined downwardly slightly from the initial end of the feed-way to the discharging end 40 thereof. The rollers are advisably of such diameter and are so near to each other, that matches being carried over them endwise, transversely of the rollers, in the manner indicated in Fig. 5, will at all times rest on at 45 least two of the rollers. For rotating these rollers all in the same direction whereby they are made to actively carry the matches from the match carrier to the tray carrier, the journal of one of the intermediate rollers, ad- 50 visably the middle one 56^a, is provided with a sprocket toothed wheel 58, on which a sprocket chain 59 runs to a sprocket toothed wheel on the driving shaft 23. At the other end this roller 56^a, and all the other rollers of 55 this series, are provided with gear wheels 60, each two of which mesh with an idle toothed wheel 60^a of a series of idle wheels mounted on arbors fixed on the frame plate 57. By 60 this means concurrent and homogeneous motion is given to the rollers 56 whereby they are made to actively transport the matches along the feedway. That the matches may be thus transported endwise and parallel with each other along this feed-way, a series 65 of partitions 61 conveniently made of sheet

metal, is provided, which partitions may be supported in position, conveniently by being secured to and made to depend from one or more rails 62, (advisably two,) secured to the frame plates 57 and extending across the 70 feed-way at a distance above the rollers. These partitions are of such length as to extend substantially the entire length of the feed-way, and advisably are of such number and placed at such little distances apart, as to 75 be adapted to receive only a few matches, perhaps three, between each two of the partitions. Also advisably the rollers 56 are grooved circumferentially, and these partitions extend down into the grooves thereby 80 preventing any displacement of the partitions, and avoiding the liability of splinters getting under the edges of the partitions.

It will be understood that the mechanism herein before specifically described includes 85 means for transferring the matches as they are discharged from the carrier of a match machine to the tray carrier consisting of an endless chain having permanent partitions and narrow compartments into which the 90 matches fall in substantially parallel positions, and that by the oscillation of the trough-way the matches are so jarred or stirred as to settle them down in the compartments in such compact manner that the trays 95 may be completely filled with matches, it being noted that the vibration of the trough-way is greatest at that part of it through which the trays come first beneath the stream of discharged and falling matches, and that 100 such vibration is gradually lessened even to the vanishing point at the pivotal point of the trough-way near the locality at which the compartments pass beyond the stream of falling matches, and that thereafter the 105 shake or vibration of the trough-way is in a reverse direction increasing somewhat in extent to the distant or rear end of the trough-way. Because the trough-way does not extend rearwardly to the extreme end of 110 the run of the tray carrier in that direction, and because the carrier is flexible and runs loosely in the tray carrier, there is no mechanical difficulty in this vibration of the trough-way even though the tray carrier is 115 carried at its rear end on the polygonal wheels 34 that are mounted in the permanently located bed 5. Having thus provided for putting the matches in proper positions into this endless tray carrier having these numerous upwardly projecting rigid partitions, it is now in order to describe the means by which these matches are transferred from this tray carrier into paper board boxes of the character commonly employed in which matches are put up for sale and use. For this purpose a box runway 63, (Figs. 1, 3, 9, 10,) is employed. This runway is conveniently formed with a thin sheet metal bottom 64 having side walls 65, and 120 125 130

overhanging top ledges 66, which ledges, side walls and bottom are secured together by screws or bolts in a common manner of similar constructions. The runway is of such size and form as to permit of the easy and free passage of the match boxes through it, except that near the lower end the side walls are thickened somewhat projecting inwardly opposite each other forming cheeks 67 so located as to engage each box frictionally with just sufficient contact to prevent the box by the mere weight of itself and succeeding boxes, from passing this point, but permitting the box and boxes to pass these cheeks under slight additional force applied to move them along. This box runway is located at and above the rear end of the upper line of the tray carrier, and is disposed in inclined position so that boxes placed therein at the upper end thereof will slide down the runway by gravity. The lower end of this runway may be supported conveniently by standards 68 fixed on the bed 5 and secured to the runway. The upper end of the runway may be supported by any convenient means, (not shown,) such for instance as the frame of the match machine or some part of the building in which the machine is set. The location and position of this runway is such that a box Y discharged therefrom in the direction of the runway will pass directly on to the tray carrier as a single tray or link thereof comes to and passes on to a face of the polygonal wheels 34, the first partition 61 of a tray entering the overturned box and engaging with the front end thereof and moving the box with the carrier while passing around the polygonal wheels and until the box separates from the carrier as hereinafter described. The match boxes are placed in this runway at its upper end bottom side up and slide down it by gravity, but as it is necessary that these boxes be discharged from the runway in proper time that a front partition of each link or tray of the tray carrier will be in position to engage the front end of the box, means are provided for regulating the movement of the boxes downwardly through the runway so as to accomplish this properly timed discharge of the boxes from the runway. For this purpose two short shafts 69 and 70 at a little distance apart are mounted transversely of the runway in hangers 71 secured to the sides of the runway and projecting downwardly therefrom, and the shaft 69 is provided with a sprocket wheel 72 and the shaft 70 with an idle wheel 73 on which an endless sprocket chain 74 runs. These wheels and the sprocket chain are located about centrally of the runway, and there is a slot in the bottom of the runway in and along which this sprocket chain runs, the outer surface of the upper line of this chain running parallel with and substantially

flush with the inner surface of the bottom of the runway. This sprocket chain 74 is provided with outwardly projecting and advisably curved blades or paddles 75 at such distance apart and so disposed, as to be adapted severally to enter one of the overturned boxes when closely succeeding each other in the runway, and engage the front end of the box and push it forward downwardly thereby pushing the preceding boxes in the line down to and including the box at the lower end of the runway and then between and held yieldingly against further forward movement by the cheeks 67 until such initial box in the runway shall have come to and been engaged by the first partition of a tray of the tray carrier.

The paddles 75 are advisably wider than the width of the sprocket chain 74, and the slot through the bottom of the runway is suitably enlarged at its ends to permit of the passage of these enlarged paddles therethrough. A sprocket chain 76 runs on a sprocket wheel 77 on shaft 69, and also on a sprocket wheel 78, on driving shaft 35, (Figs. 1, 7, 9,) driving the shaft 69 concurrently with the shaft 35 whereby the sprocket chain 74 is timed to movement with the tray carrier.

As the partitions 61 project outwardly beyond the side walls of the trays of the tray carrier a distance substantially equal to the depth of the match box Y, and as the trays or links of the tray carrier 26 are substantially as long and as wide as a match box, it will be seen that as the match box comes to the carrier and its front end is engaged by the front partition of the tray the match box will come into position on the tray so that the edges of the side walls of the box will rest on the side walls of the tray thus forming compartments in the match box complementary to the compartments in the tray, and the match box being held to the tray as it passes around the axle 35, each tray fitting to single faces of the polygonal wheels 34, the matches will pass by gravity from the compartments in the tray to the complementary or corresponding compartments in the match box, so that when the match box has come to upright position below the polygonal wheels the matches will be in properly arranged positions, and will substantially fill the match box. To hold the match boxes as they succeed one another respectively to the links or trays of the carrier while passing around the polygonal wheels a curved elongated guide 79, (Figs. 1, 2, 3, 7, 8,) is employed which is supported in position concentric to shaft 35 on the arms or extensions of bracket 36. Secured to and projecting inwardly in a downward and forward direction from the guide 79 are a number of flat elastic spring fingers 80, of such size and so disposed as to bear suitably against the bottom of

95

130

each match box while it is passing around the polygonal wheels 34, and hold it releasably to the tray of the tray carrier. From the lower end of the guide 79 a chute 81 extends in the direction of the run and movement of the lower line of the tray carrier, but diverging downwardly therefrom so that the match boxes thereon gradually separate from the tray carrier, leaving the boxes with their complement of matches. This chute 81 may terminate at any convenient locality for an attendant to remove the boxes, but it is desirable that the boxes should be automatically carried a little distance away from the box filling machine, and for this purpose the chute 81 is shown as terminating on the surface of a platform 82 in and along which and flush with the top surface thereof, the upper line of an endless apron 83 runs, and the boxes filled with matches being delivered from the chute 81 on to this apron, are carried thereby at right angles to the machine and to a distance therefrom. This apron at its inner end runs on a drum 84 fixed on a shaft 85 which is geared to a hub 86 revolvable on a stud pin, which hub is rotated by a sprocket chain 87 running also on a shaft 88 mounted in hangers depending from the bed 5, which shaft 88 has a cog wheel 89 by which it is geared to the driving shaft 23.

What I claim as my invention is:

1. In a box filling machine, an endless carrier of elongated box-like trays having upwardly extending side and end walls and transverse partitions the side walls of the trays being extended longitudinally forming ears by means of which the trays are pivoted together at their ends to form the endless carrier, wheels on which the carrier runs and by which it is moved forward constantly, a substantially horizontal trough-way in which the tray carrier travels medially along past and in and across a sheet-like falling stream of matches so disposed as to fall in substantially horizontal positions transversely of the trays and the carrier into the compartments thereof, and means adapted to vibrate the trough-way and carrier therein laterally giving the matches therein an endwise jar in the compartments and settling them down compactly in the trays.

2. In a box filling machine, an endless carrier composed of box-like open-top trays pivoted together at their ends forming the endless carrier, a horizontally disposed pivoted and swinging trough-way in which the tray carrier travels along across a wide sheet-like stream of falling matches, wheels compelling the travel of the carrier, means oscillating laterally the trough being so mounted and the means employed to oscillate it being such as to give that portion of the trough in which the trays then are that are opposite and within the sheet of falling matches a greater vibration where the trays

in their travel first come to the sheet of falling matches and less where the trays are more nearly filled with and passed beyond the supply of matches.

3. In a box filling machine, a moving endless carrier comprising elongated trough-like trays the side walls of which are extended endwise and are pivoted together as links of the carrier each tray having a transverse partition substantially at its front end and a 70 partition or partitions at the rear thereof the rearmost partition in each tray being substantially as far in front of the rear end of the tray as the partitions are from each other dividing the carrier into a continuous and 75 unseparated series of narrow compartments, a wheel or wheels on which the carrier travels and around on which the trays are carried, means for delivering boxes substantially as long as the trays in proper time and 80 in inverted position to the tray carrier at the top of such wheel or wheels in such manner that the front end of a box will be just in front of and will bear against the front partition of a tray and the rear portion of the 85 box will project rearwardly beyond the rear partition substantially to the rear end of the tray while the longitudinal edges of the boxes severally fit to the upturned longitudinal edges of the several trays, and means for 90 holding the boxes to the exterior edges of the trays while passing with the carrier around the wheel or wheels and until the box is turned over right side up.

4. In a box filling machine, a moving endless tray carrier, consisting of a series of trough-like trays pivoted together as links with transverse partitions projecting outwardly beyond the sides of the trays and dividing the carrier into a continuous and unseparated series of compartments the front partition being substantially at the front end of the tray and the rearmost partition being at a distance in front of the rear end of the tray equal to the distance of the partitions from each other, a revolving polygonal wheel or wheels on which the carrier is carried at its rear end, a box runway disposed to deliver inverted boxes substantially as long as the trays to the carrier at the top of the 100 polygonal wheel, means for timing and accurately delivering the boxes properly from the runway to the carrier in such time that the front end of each box will be caught and carried by the front partition in a tray, and 105 means for holding the boxes severally to the exterior edges of the upturned side walls of the several carrier trays and over the projecting partitions while traveling with the carrier and the wheel from top to bottom and until 110 the boxes are overturned to right side up.

5. In a box filling machine, a match feed-way, comprising a series of parallel rollers extending transversely of and forming a match - carrying feed - way inclined down- 115

- wardly from a source of match supply and a tray carrier into which the feed rollers deliver matches continuously endwise transversely of the carrier.
- 5 6. In a box filling machine, a match feedway, comprising a suitable frame, a plurality of parallel rollers disposed transversely of the longitudinal direction of the feedway, and partitions above and close to the rollers 10 and so disposed at a little distance apart that their planes extended will intersect the rollers at right angles to their axes.
7. In a box filling machine, a feedway, comprising a suitable frame, a plurality of annularly grooved parallel rollers disposed transversely of the longitudinal direction of the feedway, and partitions above and at 15 right angles to the rollers and extending down into said annular grooves, adapted 20 to separate and guide elongated material being carried over the rollers by the revolution thereof.
8. In a box filling machine, a material feedway, comprising a suitable frame, a plurality of parallel rollers near together and disposed transversely of the longitudinal direction of the feedway and in an inclined plane in the direction of the feedway, cog 25 wheels on the journals of the rollers, means 30 for rotating an intermediate one of the rollers, and idle cog wheels mounted on the frame arranged to transmit uniform motion from the driven intermediate roller to the rollers on both sides of the intermediate 35 driven roller.
9. In a box filling machine, an endless tray match carrier consisting of a series of links trough-like in form each having a bottom and upturned sides which sides are extended longitudinally forming ears that at 40 one end of each tray lap on to the sides of the adjacent tray and are pivoted thereto and transverse partitions fixed in and projecting outwardly from the trough-like links 45 dividing the carrier into a plurality of narrow transverse compartments, and intermittently rotated polygonal wheels at the ends of its lines of travel on which the carrier fits and is carried.
- 50 10. In a box filling machine, an endless tray carrier comprising trough-like links pivoted together, a plurality of transverse partitions in each trough-like link or tray the front partition being at the front end of 55 the link or tray and the partitions being higher than the depth of the tray, revolving polygonal wheels on which the carrier is carried each face of the perimeter of the wheel being of a length tangentially equal 60 to the length of a link of the carrier, and means for holding boxes of the size of a tray link bottom outward to the links exteriorly while passing with the link and wheel around the axis of the wheel from top to 65 bottom.
11. In a box filling machine, an endless match tray carrier, comprising tray-like links pivoted together and a plurality of therein fixed transverse partitions projecting outwardly beyond the tray links the front 70 partition of each tray link being at the front end of the link the link being adapted to receive thereon a match box of the same size and shape the edges of whose sides fit on the top edges of the side walls of the tray links 75 and cover over the tray link and its contents including the projecting partitions, polygonal wheels on which the carrier is carried, and means for holding the match boxes bottom outwardly yieldingly to the outer 80 edges of the tray links while passing with the carrier and wheel around the axis of the wheel from top to bottom.
12. In combination with a flexible endless tray carrier having a trough-like construction with outwardly projecting transverse partitions, means for holding boxes bottom 85 outwardly to the outer surface of the links of the carrier while moving with the carrier about the axis of its travel, and means 90 adapted to deliver boxes to and place them in time severally on the carrier and over the projecting partitions in such manner that a partition will be at the front end on the inner side of a box and at a time preceding the 95 action of the means for holding the boxes to the carrier while turning about the axis of its travel.
13. In combination with an endless carrier having a trough-like construction with 100 transverse partitions, and a polygonal wheel having tangent faces adapted to receive a tray or link of the carrier fitting thereon, of a guide about the wheel adjacent thereto and concentric to its axis, and spring fingers 105 adapted to bear yieldingly against the bottoms of boxes on the tray links of the carrier and hold them thereto while moving with the carrier and the wheel about its axis.
14. In a box filling machine, in combination with a moving endless tray carrier comprising tray links each link of which is adapted to receive and carry an inverted box thereon while transferring its load to the box, a box runway extending in the same direction as and disposed to discharge boxes on 115 to the carrier, and an endless box pusher moving in the same direction and synchronously with the tray carrier and provided with a blade or blades adapted to engage a 120 box in the runway and move it forward in proper time to fit on a passing tray link of the moving tray carrier.
15. In a box filling machine, in combination with a moving endless tray carrier comprising tray links each link of which is adapted to receive and carry an inverted box thereon while transferring its load to the box, a box runway disposed to discharge boxes on 125 to the carrier, cheeks in the runway near its 130

- discharging end adapted to bear against and prevent the forward movement of the boxes except by positive force thereon, an endless chain provided with blades disposed to enter 5 the runway and adapted to engage a box or boxes therein and push the same along the runway and past said cheeks, and means for driving the endless chain box mover in time with the tray carrier.
- 10 16. In a box filling machine, an elongated trough-way pivoted to swing horizontally, an endless tray carrier running in and along said trough-way, a slide transversely of and secured to the trough-way at a distance from 15 its pivot, a block in which said slide travels, and a pitman riding on an eccentric and connected to said slide adapted to vibrate said trough-way and the carrier traveling thereon.
17. In a box filling machine, an elongated 20 bed, a polygonal wheel or wheels mounted revolvably on the bed, a trough-way supported on the bed, another polygonal wheel or wheels mounted revolvably on the trough-way, and an endless tray carrier carried on 25 said polygonal wheels and running in said trough-way.
18. In a box filling machine, an elongated bed, a polygonal wheel or wheels mounted revolvably on the bed, a vibrating trough-way 30 pivoted and supported on the bed in front of the polygonal wheel or wheels on the bed, radial arms mounted on the trough-way at a distance from and in front of the polygonal wheel or wheels on the bed, polygonal wheels 35 mounted revolvably in the radial arms, and an endless tray carrier running on said polygonal wheels and along in said trough-way.
19. In a box filling machine, an elongated 40 bed, a polygonal wheel or wheels mounted revolvably on the bed, a vibrating trough-way pivoted and supported on the bed in front of the polygonal wheel or wheels on the bed, radial arms adjustable endwise on bolts secured to the trough-way and in and trans- 45 versely of disks on said bolts said disks having crown ratchet teeth, complementary ratchet toothed disks fixed on the trough-way, another polygonal wheel or wheels mounted in said radial arms, and an endless 50 tray carrier running on said polygonal wheels and along in said trough-way.
20. In a box filling machine, an elongated bed, a carrier carrying wheel or wheels mounted revolvably thereon at one end there- 55 of, an elongated trough-way pivoted medi- ally and supported on the bed to oscillate in reverse directions at the two ends thereof, a carrier carrying wheel or wheels mounted on the trough-way at the end thereof distant 60 from the wheel or wheels on the bed, an endless tray carrier carried on said wheels and running in said trough-way, and means for oscillating said trough-way.
21. In a box filling machine, a supporting frame, an endless tray carrier, wheels at the 65 ends of the run of the carrier on which it travels, an elongated trough-way on and along which the carrier runs medially past a sheet-like stream of matches discharged from a match making machine, said trough- 70 way being pivoted medially to oscillate horizontally the pivoted point of the trough-way being located at that side of the stream of matches beyond, in the direction of the travel of the carrier in the trough-way, where the 75 carrier passes stream of matches, and means to so oscillate the trough-way.
22. In a box filling machine, a stationary 80 bed, a revoluble carrier carrying wheel or wheels mounted on the bed, an oscillatable 85 trough-way pivoted on the bed in front of said wheel or wheels, a revoluble carrier carrying wheel or wheels mounted on the trough-way at a distance from said wheel or wheels on the bed, means for oscillating the trough- 90 way and the carrier traveling therein, a stationary curved guide about said wheel or wheels on the bed, and flat springs on said guide adapted to bear against boxes on the carrier while passing about the axis of said wheels on the stationary bed.
23. In a box filling machine, an endless 95 tray carrier consisting of elongated tray-like links pivoted together, a polygonal wheel or wheels on which said carrier fits and is car- 100 ried, means for rotating said wheel or wheels intermittently, an inclined box runway with box-retarding cheeks, an endless chain with pushing paddles that enter said runway, and means connecting said carrier having 105 pushing paddles to the driving mechanism of the carrier so that the box feeding mechanism is timed to deliver boxes past said cheeks to the tray carrier suitably on coming to said polygonal wheel or wheels. 105
24. In a box filling machine, an endless 110 tray carrier, an initial shaft having a carrier carrying wheel or wheels thereon, an intermediate shaft having an eccentric and a friction disk, a pitman riding on said eccentric and pivoted to a radial arm pivoted on said initial shaft, a pawl on the radial arm engaging releasably a ratchet wheel on the initial shaft, a driving shaft, a friction wheel splined on the driving shaft and gearing adjustably 115 with the friction disk on the intermediate shaft, an endless chain having box-pushing paddles, a chain wheel shaft, and a sprocket chain running on the chain wheel shaft and on said initial shaft. 120
25. In a box filling machine, an endless 125 flexible tray carrier, comprising a series of elongated links each having a bottom and upturned sides longitudinally forming tray-like links which sides on each link are pivoted to the sides or the two abutting links, and a plurality of permanent transverse partitions in each tray link extending from the bottom

outwardly to a distance beyond the sides of the tray links substantially equal to the depth of the sides.

26. In a box filling machine, an endless flexible tray carrier, comprising a series of elongated links each having a bottom and upturned sides longitudinally forming tray-like links which sides on each link are pivoted to the sides of the two abutting links, and a plurality of permanent transverse partitions in each tray link one of the partitions being located near the front end of the tray link and the other partition or partitions being located at points intermediate of the length of the tray link, whereby a box placed over a link will fit at its front end against the front partition and the remaining partition or partitions will divide the box into compartments while held to the carrier.
- 20 27. In a box filling machine, a box runway comprising an elongated box-like trough in inclined position through which boxes will slide freely by gravity, rigid cheeks on the side walls of the runway trough at its lower end projecting into the runway and adapted

to engage frictionally against boxes passing them and hold them against free movement by gravity, and active means in the runway adapted to push slightly compressible boxes past the projecting friction devices.

30

28. In a box filling machine, an endless flexible carrier having tray-like links, a wheel on and around with which the carrier is carried, a permanent guide about and concentric with the axis of said carrier carrying 35 wheel, flat furcate elastic fingers fixed on the guide and projecting inwardly in inclined positions therefrom and adapted to bear against the bottoms of boxes opposite the side walls thereof and hold the edges of the 40 longitudinal walls of the boxes against the edges of the side walls of the tray-like links of the carrier.

In testimony whereof, I affix my signature, in presence of two witnesses.

MORTIMER M. ROBB.
